UNITED STATES PATENT OFFICE.

WILLIAM M. SLAVIK, OF OAK PARK, ILLINOIS.

MECHANIC'S SQUARE.

Application filed March 11, 1922. Serial No. 542,818.

To all whom it may concern:

Be it known that I, WILLIAM M. SLAVIK, a citizen of the United States, and a resident of Oak Park, county of Cook, and State of Illinois, have invented certain new and useful Improvements in Mechanics' Squares, of which the following is a specification.

My invention relates to improvements in mechanics' squares, of the folding type, and has for its principal object the provision of an improved construction of this character which will be efficient in use and economical in manufacture; the present invention constitutes an improvement over my invention as set forth in Letters Patent No. 1,359,758.

A further object of the invention is the provision of selective means for rigidly locking the limb members of the square in extended relation with respect to each other.

Other objects will appear hereinafter.

The invention consists in the combinations and arrangements of parts hereinafter described and claimed.

The invention will be best understood by reference to the accompanying drawings forming a part of this specification, and in which,

Fig. 1 is a plan view of one of the sides of a square embodying the invention;

Fig. 2 is a fragmentary view of the reverse side of Fig. 1;

Fig. 3 is a fragmentary view of the square illustrated in Fig. 1 showing the same in its folded position; and

Fig. 4 is a sectional detail view, of the same, taken substantially on line 4-4 of Fig. 1.

Referring to the drawing, the preferred form of construction comprises a mechanic's square A consisting of rule members 5—the tongue—and 6—the stock—bearing scale graduations of the usual type, said tongue 5 and stock 6 being hingedly connected together, in the manner to be hereinafter set forth, and disposed substantially at right angles with respect to each other.

As best illustrated in Fig. 2 one end of the stock 6 is bevelled at an angle of 45 degrees to correspond with the adjacent bevelled edge of the tongue 5 which is also bevelled at an angle of 45 degrees. It will be noted, especially in this figure, that the width of the tongue 5 is greater than the width of the stock 6 and by bevelling the edge of the tongue 5 the bevelled edge ex-

tends diagonally to a point in the same plane as the lower edge of the stock 6, as illustrated at 7. This construction is such that a shoulder 8 is formed on the inner portion of the tongue 5, the edge of which extends parallel with respect to the adjacent edge 9 of the stock 6 and serves to relieve the hinge member, to be hereinafter set forth, of unnecessary stress and at the same time serves to increase the rigidity at the junction of the rule members.

The means for hingedly connecting the rule members together comprises a plate 10 secured to the stock 6 adjacent the bevelled edge of the same and a plate 11 secured to the tongue 5 adjacent the bevelled edge thereof, said plates having cooperating lateral ears 12 and 13 formed thereon. The lateral ears 12 and 13 are hingedly connected together by a transverse pin 14 having its opposite ends 15 in the form of a rivet head to prevent the pin from becoming displaced.

Means is provided to rigidly lock the rule members 5 and 6 in extended relation with respect to each other, this means comprises a frictionally held lock member 16 which is pivotally mounted on the tongue 5 as at 17 said point of pivotal connection being an appreciable distance from the transverse pin 14, there being a handle or finger piece 18 formed on the lock plate 16 to facilitate a pivotal movement of the same. When locking the rule members 5 and 6 in extended relation with respect to each other, the end portion 19 of the lock member 16 is provided with a bevelled exposed surface, the thinnest portion being at 20 the innermost end of the lock member. The principal object of this construction is such that when the lock member 16 is pivoted to move into engagement with the transverse pin 14 and the adjacent surfaces of the plate members 10 and 11, the same will be wedged therebetween, thus not only serving to lock the rule members in such rigid extended relation but will prevent the lock member from accidentally becoming disengaged from the transverse pin 14 when the square is in use.

From the foregoing description of the invention it will be especially noticed that I not only provide a square which can be folded and conveniently arranged in a tool box, but I also provide a lock member which not only serves to lock the rule members of the square in rigid extended relation with

respect to each other, but will remain in such locked position until manually disengaged from the transverse pin, this feature being accomplished through the medium of the 5 bevelled exposed surface of the lock member and the improvements of a device as herein set forth will be found to constitute a value greater than most devices of this character.

While I have illustrated and described the 10 preferred form of construction for carrying my invention into effect, this is capable of variation and modification without departing from the spirit of the invention. I, therefore, do not wish to be limited to the 15 precise details of the construction set forth, but desire to avail myself of such variations and modifications as come within the scope of the appended claims.

Having described my invention, what I 20 claim as new and desire to secure by Letters Patent is:

1. A foldable rule including rule members, a hinge connection between said rule members, and locking means including a 25 member pivotally carried by one of the members of the hinge connection and having a portion extending over the other member of the hinge connection when the rule members are in extended position.
2. A device of the class described comprising rule members disposed substantially at right angles with respect to each other and hingedly connected together; a pivotally mounted lock member adapted to be 30 mounted adjacent the connection of said rule members and adapted to frictionally engage the pintle of the hinge connection locking said members in rigid extended relation with respect to each other; and an operating handle on said lock member.
3. A foldable rule including rule members, a hinge connection between said members, and locking means including a wedge shaped member pivotally carried by one of the 35 members of the hinge connection and having a portion extending over the other member of the hinge connection when the rule members are in extended position, said portion being

adapted to pass under the pintle of the hinge connection. 50

4. A device of the class described comprising rule members disposed substantially at right angles with respect to each other and hingedly connected together; a pivotally mounted lock member adapted to be mounted adjacent the connection of said rule members and having a tapered portion adapted to be wedged between the pintle of said hinge connection and the adjacent sides of the hinge members of said connection; and an operating handle on said lock member. 55

5. A device of the class described comprising rule members disposed substantially at right angles with respect to each other and hingedly connected together; a lock member pivotally mounted on one of said rule members adapted to pass between the pintle of said hinge connection and the adjacent sides of the members of said hinge connection, the inner end portion of said lock member being bevelled so as to wedge between said pintle and said hinge members. 60

6. A device of the class described comprising rule members disposed substantially at right angles with respect to each other and hingedly connected together; a lock member pivotally mounted on one of said rule members adapted to pass between the pintle of said hinge connection and the adjacent sides of the members of said hinge connection, the inner end portion of said lock member being bevelled so as to wedge between said pintle and said hinge members; a shoulder formed on one of said rule members extending parallel with and engaging the adjacent side edge of the other of said members; and an operating handle on said lock member. 70 75 80 85

In testimony whereof I have signed my name to this specification in the presence of 90 two subscribing witnesses.

WILLIAM M. SLAVIK.
